UNITED STATES PATENT OFFICE.

PERL F. FLOWER, OF LA FAYETTE, INDIANA.

HOOP SETTER.

Application filed July 5, 1923. Serial No. 649,661.

To all whom it may concern:

Be it known that I, PERL F. FLOWER, a citizen of the United States, residing at La Fayette, in the county of Tippecanoe and 5 State of Indiana, have invented certain new and useful Improvements in Hoop Setters; and I do declare the following to be a full, clear, and exact description of the invention, such as will enable others skilled in the art 10 to which it appertains, to make and use the same.

This invention relates to an improved device for placing a hoop about a tub and holding the hoop in close engagement with the 15 staves of the tub with the end portions of the hoop extending in overlapping relation so that fasteners may be driven through the overlapped end portions of the hoop and into the body of the tub.

20 One object of the invention is to provide a hoop setter so constructed that a hoop may be drawn into close engagement with the body of the tub and the end portions held in close contact.

25 Another object of the invention is to provide a hoop setter in which a band of flexible metal may be placed about the tub in engagement with the hoop and the band drawn to a clamping position through the medium 30 of a turn buckle structure, the turn buckle structure including rollers for engaging the end portions of the hoop thus permitting the device to be easily operated and at the same time permitting pressure to be applied to 35 the end portions of the hoop.

Another object of the invention is to so 40 construct this device that it may accommodate itself to the size of the tub. It has been stated that the device will be used in connection with tubs and it is desired to explain that the term "tub" will include a wash-tub, an ice cream freezer tub, a barrel or any other similar tub-like container.

45 Another object of the invention is to provide an improved method of securing the upper band about the tub of an ice cream freezer, so that the hoop may be put in place or removed with the handles of the freezer still in place.

This invention is illustrated in the accompanying drawings, wherein:

Figure 1 is a top plan view showing the device applied to a tub.

Figure 2 is a side elevation of a tub with the device in position thereon.

This device is for use in holding a hoop 1 about a barrel or tub 2 so that the hoop can be placed about a tub such as an ice cream freezer tub with the handles of the tub in place. At the present time, it is customary to form a hoop with the overlapped end portions riveted together and then place the hoop upon the tub. If for any reason, it is desired to remove the upper hoop of the tub, it is necessary to remove the handles before this can be done, as the handles would be in the way. With this improved construction, the hoop will be secured about the tub above the handles and if it is desired to remove the hoop, it is simply necessary 70 to remove the securing nails 3 and remove the hoop. The hoop can then be put back in place and held securely in position with the ends overlapping and the fasteners then driven back into place.

In order to secure the hoop about the upper portion of the tub, there has been provided a flexible tub-encircling member 4, preferably in the form of a band. This band may well be formed of flexible steel or other 80 suitable material. One end of this flexible band 4 is connected with a hook 5 and the other end is connected with an eye 6. This band is to be placed about the tub in overlying relation to the strip which is to form 85 the hoop 1 and the end portions of this band 4 will be drawn toward each other so that the band and hoop forming strip will be drawn into close fit about the tub with the end portions of the hoop-forming band or 90 strip extending in overlapping relation.

In order to draw the end portions of the band 4 toward each other, there has been provided a turn buckle 7 having the usual threaded rods 8 and 9, the rod 9 terminating 95 in a large hook 10 for passing through the eye 6 and the rod 8 terminating in a smaller hook 11 for engaging one of the links of a

chain 12 which will be carried by the hook 5. Each of the threaded rods carries a yoke 13 which extends transversely of the turn buckle to straddle the end portions of the 5 hoop forming strip 1. These yokes carry rollers 14 for engaging the tub above and below the hoop.

When it is desired to put a hoop upon a barrel or tub, the strip which is to form 10 the hoop will be placed about the tub and the band 4 will then be passed about the tub in overlying relation to the hoop forming strip 1. The hook 10 will be engaged with the eye 6 and the hook 11 will be engaged 15 with one of the links of the chain 12. It is of course understood that when first put in place, the turn-buckle is extended. After the device is in place, the turn buckle is tightened, and the hoop 1 will be 20 pressed about the tub both by the pulling and compressing action of the band 4 and also by the pressure of the rollers 14 which serve to retain the end portions of the strip 1 in engagement with the tub. After the 25 turn buckle has been tightened as much as possible, the fastener nails 3 will be driven into place through the overlapped end portions of the hoop forming strip 1. When it is desired to remove the hoop, it is simply 30 necessary to remove the nails 3 and the end portions of the strip forming this hoop will be released. The hoop can then be easily 35 put back in place as previously explained and after being again secured, the turn buckle loosened to permit the hoop setting device to be removed and put away until again needed. It will thus be seen that there has been provided a device by means of which a hoop can be easily put in place 40 and secured tightly about a tub or barrel and further that there has been provided a device by means of which a hoop can be secured about an ice cream freezer tub with the handles in place and the hoops removed 45 and replaced without it being necessary to remove the handles of the tub.

I claim:

1. A method of forming a hoop for a 50 tub comprising placing a strip about the tub passing a tightener about the tub in overlying relation to the strip and tightening the tightener to hold the strip tightly about the tub with its end portions overlapping, and passing fasteners through the 55 overlapped end portions of the strip into the tub.

2. A method of forming a hoop for a 60 tub comprising placing a strip about the tub, applying a tightener to tighten the strip about the tub with its end portions in overlapped relation and passing fasteners through the overlapped end portions of the strip into the tub.

3. A hoop setter comprising a flexible

band for extending circumferentially in 65 overlying relation to a hoop forming strip placed about a tub, tightening means for drawing the ends of the band toward each other to hold the hoop forming strip tightly about the tub with the end portions of the 70 strip in overlapping relation, and means carried by said tightening means for engaging the tub and holding the end portions of the strip in overlapped and contacting relation, while fasteners are driven through the overlapped end portions of the strip into the tub. 75

4. A hoop setter comprising a flexible band for extending circumferentially in 80 overlying relation to a hoop forming strip placed about a tub, tightening means for drawing the ends of the band toward each other to hold the hoop forming strip tightly about the tub with the end portions of the strip in overlapping relation, and roller means carried by said tightening means for 85 straddling the end portions of said strip and engaging the tub above and below the strip.

5. The structure of claim 4 having the 90 rollers grooved for passage of the hoop forming strip between the tub and rollers with the end portions of the rollers engaging the tub.

6. A hoop setter comprising a flexible 95 strip, a turn buckle having threaded rods at its ends the threaded rod at one end being loosely connected with one end of said strip, means adjustably connecting the threaded rod at the second end of the turn buckle with the second end of the strip, and 100 means carried by the turn buckle for engaging a tub and straddling a hoop held about the tub by said hoop setter.

7. A hoop setter comprising a flexible 105 strip, engaging elements at the ends of said strip, a turn buckle having its threaded rods terminating in engaging elements, the engaging element of one rod being loosely connected with the engaging element at one 110 end of said strip, means adjustably connecting the engaging element of the second rod with the engaging element at the second end of said strip, and rollers rotatably connected with and extending transversely of the rods for engaging a tub and straddling 115 a hoop compressed about a tub by the hoop setter.

8. A hoop setter comprising a flexible 120 strip, engaging elements at the ends of said strip, a turn buckle having threaded rods terminating at their outer ends in hook elements, the hook of one of the rods having engagement with the engaging element at one end of said strip, a chain releasably engaged with the hook of the second rod 125 and with the engaging element at the second end of the strip, yokes carried by and extending transversely of the rods adjacent

the hook elements, and rollers carried by said yokes for engaging a tub and straddling a hoop held about a tub by the hoop setter.

5 9. A hoop setter comprising a flexible member adapted to extend circumferentially in overlying relation to a hoop forming strip placed about a tub, and tightening means for drawing the ends of the band to-
10 ward each other to hold the hoop forming

strip tightly about the tub while it is being fastened.

10. A structure as specified in claim 9: together with roller means for holding said drawing means in outwardly spaced relation ¹⁵ with the tub.

In testimony whereof I have hereunto affixed my signature.

PERL F. FLOWER.
